UNITED STATES PATENT OFFICE.

JOHN J. LARKIN, OF ST. LOUIS, MISSOURI, AND ROBERT L. GORDON, OF BARTLESVILLE, OKLAHOMA, ASSIGNORS TO BELL PUMP COMPANY, OF BARTLESVILLE, OKLAHOMA, A PARTNERSHIP COMPOSED OF JOHN J. LARKIN, ROBERT L. GORDON, AND A. W. SHULTHIS, OF INDEPENDENCE, KANSAS.

OIL-WELL PUMP.

1,423,860.

Specification of Letters Patent. Patented July 25, 1922.

Application filed September 1, 1921. Serial No. 497,570.

To all whom it may concern:

Be it known that we, JOHN J. LARKIN and ROBERT L. GORDON, citizens of the United States, residing at St. Louis, Missouri, and 5 Bartlesville, Washington County, Oklahoma, have invented a certain new and useful Improvement in Oil-Well Pumps, of which the following is a full, clear, and exact description, such as will enable others skilled 10 in the art to which it appertains to make and use the same, reference being had to the accompanying drawings, forming part of this application.

Our invention relates to oil well pumps 15 and consists in improvements in the type of pump disclosed in Bell Patent No. 991,600.

The pump there shown has been manufactured in large quantities and has gone into extensive use, but the parts have been 20 designed for a given stroke, and increasing the stroke destroys the effectiveness of the pump although a greater stroke is often desirable. One object of our invention is to provide a working barrel for such a pump 25 which, whether comprising original or refitting equipment, will permit the use of any requisite stroke.

We have also found that the settling of sand about the pump working barrel impairs 30 its operation, and another object of our invention is to eliminate the accumulation of sand around the pump.

Additional objects and advantages of our invention will appear in the following description and in the accompanying drawings forming part of this specification, in which—

Figure 1 is a vertical section through the lower end of a well equipped with our improved pump;

40 Figure 2 is a detail of the working barrel drawn on an enlarged scale, and,

Figure 3 is an enlarged view of the lower end of one of the pump tubes.

Figure 4 shows a modified form of the 45 working barrel.

The outer wall 1 of the pump is joined to the well tubing 2 and forms an extension of the same. A bottom casting 3 closes the lower end of the pump except for the entry 50 ports for the oil.

Mounted in the bottom casting 3 is a pump working barrel 4 consisting of a length of tubing which is crimped at a substantial dis-

tance above its lower end to provide a seat 5 for the pump standing valve 6.

A hollow pump piston 7 is slidable within working barrel 4 and is equipped with the usual plunger 8 and check valve 9. The upper end of piston 7 is secured to a clutch housing member 10, and depending from member 10 and surrounding working barrel 4 is a short downtake tube 11. Depending from member 10 and surrounding tube 11 is a downtake tube 12 which extends substantially below the lower end of tube 11.

As explained in the above mentioned patent, the space between the working barrel 4 and tube 11 forms a chamber for the reception of gas the pressure of which prevents the passage of oil containing sand, etc., to 70 the plunger cups and valve.

The lower end of tube 12 is deeply recessed or notched to provide teeth 13 which are adapted to be thrust into the sand, etc., settling to the bottom of the pump and to 75 continually agitate same so that it may be discharged with the oil from the well. The lower ends of teeth 13 are preferably beveled for more effective work on the pump deposits.

The commercial pump manufactured under the above mentioned patent, was designed for a 20" stroke and was only effective when the stroke did not exceed that distance. This is because when the stroke exceeded 80 20", the bottom of tube 11, on the upstroke, rose so close to the top edge of working barrel 4 that the gas chamber normally formed by the telescoping of the tube 11 with the working barrel no longer existed 85 and consequently the fluid surrounding barrel 4 was permitted to rise on the inside of the tube 11 and flow over the top of the working barrel carrying the destructive sand with it.

In practice, it was found that in certain circumstances it was necessary to have a pump which could be operated with a stroke exceeding 20", and to adapt the manufactured pump for this purpose, it became 100 necessary to increase the length of the tubes 11 and 12 and to correspondingly increase the height of the working barrel 4 and to increase the length of the outer shell 1.

Because of the gas which tends to accumulate between the standing valve 6 and

- plunger 8, it is necessary that at the bottom of the pump stroke, the lower end of the plunger shall come as near as possible to the top of the standing valve without bumping same. Hence, when tubes 10 and 11 are lengthened and the top of barrel 4 raised, it becomes necessary either to make piston 7 longer or to support the standing valve 6 higher up from the bottom of the pump.
- 10 As the lengthening of piston 4 is both difficult and expensive, we prefer to provide a seat for the standing valve spaced from the bottom of the pump.

This was previously accomplished by 15 threading the lower interior of working barrel 4 and securing an extension therein which raised the working barrel the necessary distance and the lower end of which was screwed into the bottom casting 3. This necessitated the cutting of threads on the interior of the lower end of the working barrel and at both ends of the extension, which threads had to be very accurate in order to preserve the alignment of working barrel 4 20 and outer shell 1. It necessitated a new bottom casting adapted to fit the smaller diameter of the extension and consequently the stocking of two sizes of bottom castings by both the manufacturer and the operator.

25 30 With our improvement, the only additional operation on the working barrel is that of forming the seat 5 for the standing valve, an operation which is easily and quickly completed with the proper tool and 35 in which extreme accuracy is not essential.

If preferred the standing valve seat may be provided, as shown in Figure 4 by in-

serting a pipe 14 of smaller diameter in barrel 4 and securing the two together so that the upper end 15 of pipe 14 is located 40 at the same height as the crimp in pipe 4 in Figure 1.

We are aware that other modifications of our invention may be made without departing from the spirit thereof, as indicated 45 by the following claims:

What we claim is:

1. In an oil well pump, a casing, a bottom casting therefor, a working barrel seated in said bottom casting, a standing valve seated in said working barrel at a substantial distance above said bottom casting, a reciprocating plunger in said working barrel, and a discharge chamber surrounding said barrel, the wall of which chamber reciprocates 55 with said plunger, and the lower end of said wall, at the bottom of its stroke, extends below said standing valve but is spaced substantially from said casting.

2. In an oil well, a pump device comprising a working barrel adapted to cooperate with the pump casing to form a pocket and provided with a standing valve seat at a substantial distance above the bottom of the pocket, a discharge chamber wall surrounding said barrel and extending into said pocket and provided with a toothed lower end which extends below said standing valve upon the down stroke of the pump.

In testimony whereof we hereunto affix 70 our signatures this 27th day of August, 1921.

JOHN J. LARKIN.
ROBERT L. GORDON.
